ENGINE TIMER CONSTRUCTION

Irving N. Eustis and Neil J. McDonald, Fairmont, Minn., assignors to Fairmont Railway Motors, Inc., Fairmont, Minn., a corporation of Minnesota

Application February 27, 1939, Serial No. 258,593

4 Claims. (Cl. 200—30)

This invention relates to improvements in engine timer constructions and it consists of the matters hereinafter described and more particularly pointed out in the appended claims.

The timer construction with which the present invention is more especially concerned is of the kind which includes a resilient blade-like member that carries a contact point and which member is directly actuated by a wiper on the fly wheel of the associated engine so that its contact has a make and break engagement with a stationary contact forming a part of the timer construction.

With the resilient contact carrying blade as heretofore employed, one end was fixed and the other end was free to vibrate but such a blade has a definite maximum speed after which it fluttered when actuated and this was detrimental to the contact points of the timer, requiring frequent cleaning, adjustment and other servicing.

One of the objects of the present invention is to provide, in a timer of this kind, a simple and improved means for opposing fluttering of the blade at certain engine speeds so that the engine may be operated at higher speeds without a detrimental effect upon the timer contact points.

Another object of the invention is to provide a timer construction of this kind in which it is practical to embody a timer condenser therein as a part of the same.

A further object of the invention is to provide a simple and novel mounting for the stationary contact of the timer and whereby said contact is cushioned against the vibratory engagement 5 of the movable contact so as to reduce wear between the two contacts.

Another object of the invention is to provide a timer construction which may be easily removed from and applied to the engine without 0 requiring the removal of the balance or fly wheel thereof.

Again, it is an object of the invention to provide a timer construction wherein the arc of contact between the vibrating blade and the fly 15 wheel driven blade actuator may be more easily adjusted without disturbing the setting of the timer contact points.

Again it is a further object of the invention to provide a timer bracket that may be so arranged 50 on the crankshaft bearing of an engine that the timed relation of the crankshaft and the timer contacts may be varied without altering the length of contact or the relation of the contacts to each other.

55 The above mentioned objects of the invention,

as well as others, together with the advantages thereof will more fully appear as the specification proceeds.

In the drawing:

Fig. 1 is a top plan view of an engine timer 5 construction embodying the preferred form of the invention in connection with related parts of the associated engine.

Fig. 2 is a view of the same in side elevation, with parts shown in longitudinal vertical section 10 better to illustrate the structure thereof.

Fig. 3 is a vertical detail sectional view as taken on the line 3—3 of Fig. 1.

Fig. 4 is a detail view of parts appearing in Fig. 2 and shows the positions thereof when the 15 contact points are engaged.

Referring now in detail to that embodiment of the invention illustrated in the drawing, 5 indicates a bearing boss for the crank shaft 6 of an internal combustion engine and to which shaft 20 is fixed the hub 7 of the balance or fly wheel 8 of the engine.

9 indicates the frame of the timer as a whole and which frame is in the form of a split collar comprising top and bottom substantially semi-circular collar parts 10 and 11 adapted to surround or embrace the bearing boss 5 inwardly of the fly wheel.

The collar parts 10 and 11 are provided with opposed ears 12 and 13 respectively and bolts 14 30 are inserted through the ears of one collar part to be threaded into the ears of the other collar part and whereby the frame 9 as a whole is clamped in position on the boss 5. The top collar part 10 is formed on one side of the center of the shaft 6 with a lateral arm 15 and is formed on the other side of the center of the shaft with an upwardly and outwardly extending arm 16.

A lateral extension 17 is pivotally connected to the arm 16 by a bolt 18. The arm 15 which is 40 apertured as shown for the attachment of a shift lever, is formed on that side facing the wheel 8 with a boss 15a. By means of said arm, the timer as a whole may be turned about the axis of the crankshaft, so as to alter the time relation 45 between the crankshaft and the timer contacts without changing the relation of said timer contacts to each other.

19 indicates a horizontally disposed member arranged with one end 20 overhanging the extension 17 and with the other end 21 overhanging the boss 15a. The end 21 is formed with a shoulder 22 facing toward the end 20 as best appears in Fig. 2.

23 indicates as a whole the movable contact 55

carrier of the timer. In this instance, said carrier includes top and bottom spring fingers or blades 24 and 25 both engaged at one end between the extension 17 and end 20 of member 19. A bolt 26 passes up through said parts from below to receive a nut 27 at the top end, which extends through said end part 20. Said nut and bolt secure a terminal clamp 28 in place. The blade 24 is of such length that the extremity of its other end normally engages the shoulder 22 and in said end is an opening 24a as appears in Fig. 4. The bottom blade 25 which is shorter than the top blade, terminates short of said shoulder 22 as best appears in Fig. 2 and on the upper surface of said end is fixed a contact 29 that projects up through the opening 24a in the blade 24.

30 indicates the stationary but adjustable contact of the timer adapted for a make and break engagement with contact 29. This contact is in the form of a screw that is carried by the member 19 in line with and above the contact 29. In this instance said screw has a cushioned insulated engagement in the member 19 by reason 25 of the following construction. In the member 19 coaxially with the contact 29 is a vertically arranged opening 19a in which is engaged a rubber bushing 31 having inner and outer metallic sleeves 32-33, the outer sleeve having a snug 30 fit in the opening 19a. This bushing structure is locked in place by a set screw 34 carried by said member 19. The inner sleeve 32 is internally threaded for screw threaded engagement by the contact 30 which is in the form of a screw 35 for this purpose. A fibre washer 35 is placed on the top end of said bushing and a terminal connection 36 is placed on said contact above the washer, after which a nut 37 is applied to the top end of the contact 30 to clamp the terminal 40 connection in place. This structure not only provides an engagement for the contact screw 30 which cushions the engagement of the contact 29 therewith but it also insulates the contact 30 from the member 19. In the bottom surface of 45 the member 19 at a point between its ends is a downwardly facing recess 38 in which a helical expansion spring 39 is engaged so that its bottom end bears against the top surface of the top blade or finger 24.

50 The member 19 is formed toward the end 20 thereof with a cylindrical housing 40 that is open at its ends. In said housing is located a condenser unit 41. That end of said unit facing the terminal connection 36 has one end of a conductor 42 connected thereto and the other end of said conductor is connected to the contact 30 by reason of its being clamped in between the washer 35 and terminal 36 by the nut 37. The condenser unit 41 is inserted into the housing 40 55 from the opposite end thereof and to secure the same against accidental dislodgment, a portion 43 of a washer 44 arranged between the terminal connection 26 and the end 20 of the member 19 is bent upwardly to close the associated end 60 of the housing 40.

The hub 7 of the wheel 8 carries a longitudinal bolt 45 and a contact wiper 46 is fixed to the inner end thereof. This member 46, which is herein shown as annular, is disposed in a recess in 70 said hub so as to be located in the plane of the vibrating blade or finger 23 as a whole. A portion of said contact wiper 46 projects beyond the periphery of the hub 7 so that in the rotation of the fly wheel, said portion will engage the blade 75 or finger 23 with a wiping lifting action to ac-

tuate the same. Should that portion of the member 46 that engages the blade or finger 23 become worn, the bolt 45 may be turned to bring a new portion of said member into operative relation with respect to said blade or finger.

The member 19 (and the parts carried thereby) is capable of a limited relative movement about the axis of the bolt 18 for adjusting the position of the vibrating blade or finger 23 with respect to the member 46. The structure providing such movement is as follows, and which best appears in Fig. 3. A bolt 47 extends through the end 21 of the member 19 and has a threaded engagement at its bottom end in the boss 15a. On said bolt is placed a washer 48 which rests on the boss and a pin 49 extends through the bolt below the washer which limits the position of said washer in one direction on said bolt. An expansion coil spring 50 surrounds that part of the bolt between the underside of the end 21 of the member 19 and the washer 48.

By turning the bolt 47 in one direction so as to compress the spring 50, the member 19 is swung clockwise as viewed in Fig. 2, about the bolt 18 as an axis and this moves the blade or finger 23 toward the hub 7. By turning the bolt in the other direction, the spring 50 expands and swings the member 19 in the opposite direction so that the finger moves away from the hub. Thus, by turning the bolt 47 in one direction or the other, it is possible to adjust relatively, the member 46 and the blade or finger 23.

When the engine is in operation, the member 46 engages the blade or finger 23 and flexes the two leaves 24-25 thereof upwardly to engage the contact 29 with the contact 30, thus closing a circuit to the spark plug (not shown) of the engine. In this upward movement of the blades 24-25, the spring 39 is placed under tension. As the upper blade 24 has the enlarged hole 24a in that end associated with the contact screw 30, said end can flex upwardly to partially surround the contact end of the screw as best appears in Fig. 4. It is to be noted that the spring 39 is disposed above but in the plane of the axis 4 of the shaft 6. Thus, as the wiper member 46 passes through this plane, the spring 39 coacts with the natural tendency of the blades, to return them to normal position wherein the contact 29 is out of engagement with the contact 30 and 5 wherein the free end of the blade 24 has engaged its stop shoulder 22 on the member 19. Thus, the blade 24 functions to dampen the fluttering of the contact carrying blade 25 and this dampening action of the blade 24 is assisted by the 5: expansion action of the spring 39.

With the arrangement described, the contact carrying blade 25 may be rapidly flexed into contact engaging position with the contact 30 but so soon as the member 46 passes through the 60 plane of the shaft 6 and spring 39, it cannot flutter under vibration because the fluttering action is prevented by the combined action of the blade 24 and the spring 39. Thus, high speed engine operation is greatly improved.

It is apparent that by reason of the cushion mounting of the contact member 30, the mechanical wear between the two contact points is materially reduced so that the period of usefulness of said points is greatly increased.

It is pointed out that in winter operation of the engine, it is necessary to open the points 29-30 considerably further than for summer operation. However with the structure above described, it is possible to set the arc of contact so 75

that the time of point closure is the same as for summer operation. Thus, with the points set wide, the blows between the points will be sufficient to break off such ice that forms on said points and which would otherwise prevent the timer from operating.

The construction described provides for the complete adjustment of the length or period of contact which remains constant for all speeds but can easily be set to give optimum operation for all imposed conditions and to compensate for wear of moving parts and contacts.

While in describing the invention we have referred in detail to the form, arrangement and construction of the parts, the same is to be considered only in the illustrative sense so that we do not wish to be limited thereto except as may be specifically set forth in the appended claims.

We claim as our invention:

1. An engine timer embodying therein a bracket adapted to be secured to a crank shaft bearing of an engine, a relatively elongated supporting member arranged transversely of the crankshaft, means for supporting said member at its end portions from and in spaced relation above said bracket, a stationary contact carried by said supporting member and having a contact point disposed at the bottom side thereof, resilient vibratile means comprising a plurality of spring blades disposed between said supporting member and said bracket, one of said blades being the longer, one end of said blades being secured to one end of said supporting member, with the other end of the longer blade normally engaged with a shoulder on the bottom of said supporting member, the last mentioned end of said longer blade having an opening through which a contact point on the other blade extends to have a make and break engagement with the first mentioned contact point in the vibration of said blades, and means carried by and depending from said supporting member for engaging said resilient means at a point between said one end of said blades and said stationary contact for opposing the fluttering of said resilient means in the vibration thereof.
2. An engine timer embodying therein a bracket adapted to be secured to a crankshaft bearing of an engine, a relatively elongated supporting member arranged transversely of the crank shaft, means for supporting said member at its end portions from and in spaced relation above said bracket, a contact member, means carried by one end of said supporting member and in which said contact member is adjustably engaged to space its point the desired distance below said elongated member and which means insulates said contact member from the supporting member, resilient vibratile means comprising a plurality of spring blades disposed in the space between said bracket and said supporting member and below said contact point and secured at one end to the other end of said supporting member and carrying a second contact point for a make and break engagement with the first mentioned one
3. An engine timer embodying therein a bracket adapted to be secured to a crankshaft bearing of an engine, a relatively elongated supporting member arranged transversely of the crankshaft, an arm pivotally mounted on said bracket, means for fastening one end of said member to said arm and whereby said member is capable of a limited rocking adjustable movement on said bracket, means connecting the other end of said supporting member to said bracket and which means is operable to move said supporting member about the pivotal axis of said arm, a contact member associated with the last mentioned end of said supporting member with a point disposed toward the bottom side of said member, a resilient vibratile means positioned between said bracket and said member and including a plurality of spring blades, one of which is shorter than the other and carries a contact point that extends through the longer one to engage the point of the first mentioned contact, one end of both blades being clamped between said arm and the associated end of the supporting member, a shoulder on the bottom portion of the supporting member with which the other end of the longer arm is normally engaged, and means positioned between the mid portions of said supporting member and said spring blades for opposing the fluttering thereof in the vibration of said blades.
4. An engine timer embodying therein an annular-like bracket adapted to be clamped in embracing relation upon a crank-shaft bearing of an engine and to be adjusted into different angular positions thereon, a relatively elongated supporting member arranged transversely of said crankshaft, means for pivotally supporting one end of said supporting member upon said member and in spaced relation above said bracket, means for connecting the other end of said supporting member to said bracket and which means is operable to move said supporting member about its pivotally supported means into different positions on said bracket, a contact member associated with the last mentioned end of said supporting member and having a point disposed below the same, a resilient vibratile means positioned between said bracket and said supporting member and secured at one end to the pivoted end of said supporting member, said resilient vibratile means carrying a contact point towards its other end for a make and break engagement with said first mentioned point, and means arranged between a mid portion of the bottom of said member and the mid portion of the top of said resilient vibratile means for opposing the fluttering of said last mentioned means in the vibration thereof.
